UNITED STATES PATENT OFFICE.

CHARLES H. HODGKINS, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROLLER.

1,354,191.

Specification of Letters Patent. Patented Sept. 28, 1920.

Application filed June 6, 1916. Serial No. 101,905.

To all whom it may concern:

Be it known that I, CHARLES H. HODGKINS, a subject of the King of Great Britain, and a resident of Pittsburgh, in the county 5 of Allegheny and State of Pennsylvania, have invented a new and useful Improvement in Controllers, of which the following is a specification.

My invention relates to controllers for 10 electric motors and particularly to controllers that are employed in connection with alternating-current motors requiring heavy currents in starting under load.

My invention has for one of its objects to 15 provide a mechanism of the character indicated above in which the switch mechanism operates with a quick movement to establish and to open the circuits controlled by it.

A second object of my invention is to provide 20 a controller having switch mechanism that is simple in construction and the coacting parts of which may be readily assembled.

According to the present invention, I provide 25 a controller having switch mechanism constructed of punched parts that may be readily assembled without the use of pins or rivets such as are necessary in switch mechanism of the usual construction. The coacting parts are provided with swaged projecting portions which constitute pivotal connections. The movable switch members are provided with relatively short lever arms that are controlled by rotatable cams 30 to effect a quick or snap movement in opening and in closing the switches.

The details of my invention will be described in connection with the accompanying drawings, in which Figure 1 is a view, 40 partially in elevation and partially in section, of a controller constructed in accordance with my invention. Fig. 2 is a view, similar to Fig. 1, but taken at right angles thereto. Figs. 3, 4, 5, 6, 7 and 8 are views 45 of details of the switch mechanism.

Referring particularly to Figs. 1 and 2, the controller comprises a casing 1 having a stationary part 2 that is adapted to be secured to any suitable support and a removable part 3 which may constitute a tank for oil in case the controller is employed in connection with high-voltage circuits. The part 3 is attached to the stationary part 2 by means of latching mechanisms 4. A cover

member 5 is loosely hinged to the member 3 55 by means of mutually engaging hook portions 6 and is secured in position by a latching mechanism 7 that is located at the top of the casing.

The switch mechanism comprises two rows 60 of stationary contact members 8 and 9 that are mounted upon suitable supports 10 of insulating material and are respectively located near the front and the rear of the casing. Movable contact members 12 and 13, 65 which coact with the stationary contact members 8 and 9, respectively, are secured to members 14 that are pivotally supported by stationary members 15.

The switch mechanism is controlled by a 70 series of cam members 16 which correspond, in number, to the oppositely disposed pairs of switches. The cam members 16, which are of insulating material, such as, for example, fiber, are mounted upon a polygonal shaft 75 17 and are separated by spacing sleeves 18, also of insulating material. The shaft 17 is mounted for rotation in bearings 19 that are secured to the side walls of the casing. An operating handle 20 is secured to one end of 80 the shaft 17.

The operating shaft 17 and its connected parts are normally retained in their respective illustrated or inoperative positions by a centering device 21 which comprises a stationary pin 22, two oppositely disposed curved arms 23 that are pivotally supported by the shaft 17, a spring 24 which resists the separation of the arms 23 and a pin 25 85 that is mounted upon an arm 26. The arm 26 is secured to the shaft 17 for rotation therewith and extends upwardly therefrom.

Means are provided, also, for insuring that the operating handle can be moved in one direction only from its inoperative position. A pivotally mounted latching member 27 is provided with a notch 28, one side 95 of which is inclined to the axis of the member 27 and projects laterally beyond the other side of the notch which is normal to 100 the axis of the shaft. This arrangement insures that the switch mechanism can be operated only in a definite sequence in starting the motor. When the pin 25 is seated in the notch 28 and the handle is operated from its 105 central position to its starting position, the pin 25 is actuated to the right, as viewed in Fig. 2, to raise the latching member 27,

whereupon the handle may be actuated in the opposite direction to establish the running connections of the motor, if the handle is moved rapidly.

5 The arm 26 is provided, at its upper end, with a projecting pin or rod 30 which coacts with a latching mechanism 31 to retain the arm 26 and its connected mechanism in their respective running positions. The latching mechanism 31 comprises a pivotally mounted arm 32 that is provided with a hook 33 extending at right angles thereto. The hook 33 is provided with a notch 34 and an inclined portion 35 for coacting with the pin 30. An electromagnet 36 retains the arm 32 in a vertical position when the pin 30 has been actuated into engagement with the notch 34. The switching mechanism and the handle 20 are retained in their respective running positions by the electromagnet 36 except upon failure of voltage, opening of the circuit of the electromagnet coil or other abnormal conditions to be later described.

25 The cover member 5 is provided with a member 37 of insulating material which projects downwardly a sufficient distance to engage the arm 32 in case the latter is in its vertical position when the cover member 5 is removed from the casing. By means of this arrangement, it is impossible to remove the cover member 5 and allow the switch mechanism to remain in its running position.

35 The several parts of a transformer 38, which is connected in circuit with the motor to reduce the voltage applied to the latter in starting, are held in operative relation to each other and are secured to the casing member 2 by means of bolts 39 and spacing sleeves 40. A fuse block 41 is secured to the transformer 38 and is accordingly supported by the bolts 39.

Reference may now be had to Figs. 2 to 45 8, inclusive, in which the details of the switch mechanism are clearly shown. The members 15 are constructed by punching a substantially cruciform member from a sheet of metal and then bending a pair of oppositely extending arms 44, which have been provided with holes 45 near their outer extremities, at right angles to the other arms. A third arm 46 is also bent at right angles to the plane of the member to constitute a support for a spring 47.

55 The movable members 14 of the switch mechanism are similarly formed by punching from a sheet of metal. Two arms 48, which extend at an angle from the remaining arms, are swaged at intermediate portions to provide annular projections 49. The extremities of the arms 48 are provided with similar projections 50 which extend in the opposite direction. The arms 48 are 65 then bent at right angles toward each other

to assume the relative positions illustrated in Figs. 5 and 6. A third arm 51 is bent at an intermediate portion to coact with the spring 47. A bar 52 is riveted or otherwise suitably connected to the members 14, for carrying the one or the other of the contact members 12 and 13, as the case may be.

In assembling the switch mechanism, the arms 48, which are of resilient material, are separated to a sufficient distance to permit the insertion of a roller 53 which is rotatably supported by the annular projections 49. The arms 44 of the stationary member 15 are then spread apart in order to permit the insertion of the movable member 14 to such position that the annular projections 49 register with the holes 45. The arms 44 are then released and the members 14 and 15 are pivotally connected by the projections 49 and the holes 45. The spring 47 is then inserted between the arm 46 and 51 and a flexible shunt conductor 54 is secured to a binding post 55.

The bearing members 19, for supporting the operating shaft 17 are constructed by forming plate members 56 that are provided with suitable central openings 57 and hook members 58 and then casting bearing members 59 of suitable bearing material to form an integral structure. To secure the bearings 19 in position, the plate members 56 may be electrically welded or otherwise suitably connected to the casing 1.

It may be assumed that the switch mechanism is electrically connected in any suitable manner (not shown) to the primary windings of an alternating-current motor and that the various parts occupy their respective illustrated or inoperative positions. To start the motor, the operating handle 20 is first actuated to rotate the shaft 17 in a clockwise direction, as viewed in Fig. 2. The cam members 16, which rotate with the shaft 17 and are in engagement with the rollers 53, then permit the springs 47 to effect the engagement of contact members 12 and 8 to establish the starting connections of the motor. During the operation just described, the arm 26 and the pin 25 move to the right and the latch member 27 is raised to its uppermost position by the pin 25.

When the motor has attained a desired speed, the handle 20 is actuated quickly in the opposite direction to its running position to effect a quick separation of the contact members 12 and 8 and to permit a correspondingly quick engagement of the contact members 9 and 13. A rapid movement of the operating mechanism is made necessary by reason of the fact that the latch member 27 engages the pin 25 and retains the various parts in the respective inoperative positions unless the pin 25 is moved across the notch 28 before the latch member 27 is actuated by gravity to engage the pin. 130

When the arm 26 and the pin 30 are moved to the running position, the latter engages the arm 32 to actuate the latter to its vertical position in which it is retained by the 5 electromagnet 36. The hook member 33 is in such position that it is not engaged by the pin 30 during the movement above described. As the arm 32 is moved to its vertical position, the hook member 33 moves upwardly 10 and the pin 30 is thereby seated in the notch 34. The arm 26 and the various operating parts to which it is connected are retained in their respective running positions under all normal conditions. The arm 32 is released, however, upon a failure of voltage 15 and the resultant deenergization of the magnet 36 or upon the opening of the circuit of the latter by any suitable means. The arm 32 will be withdrawn from its vertical position to release the arm 26 in case the cover member 5 is removed from the casing while the various parts are in operative position by reason of the engagement of the arm 32 by the member 37.

25 In case the arm 32 is released by the electromagnet 36, the arm 26 will be returned automatically to its intermediate position by the centering device 21. When the arm 26 is actuated in either direction from its 30 illustrated position, the pin 25 causes a movement of one of the arms 23 about its point of pivotal support. The spring 24, which is attached to the other arm 23, is placed under tension, since the last mentioned arm is held 35 in its normal position by the stationary pin 22. It is obvious, therefore, that movement of the arm 26 in either direction places the spring 24 under tension and that the arm 26 is restored to its intermediate position when 40 it is released by the latching mechanism 31 or when the handle 20 is released by the operator without first securing the switch mechanism in position by means of the latching mechanism 31.

45 It will be noted that I provide a controller having an operating mechanism for insuring the quick engagement and disengagement of the contact members of the switch mechanism. The bearing members 50 for the operating shaft are of simple construction and are arranged to be attached in position with a minimum amount of labor. The switching mechanism is constructed of parts that may be formed by punching and 55 which may be assembled without the use of bolts, rivets or similar devices. The switching mechanism may be readily taken apart for the purpose of inspection or repair. The fuse block is located in such position that 60 the fuses carried by it may be readily accessible for replacement or inspection without the necessity of disturbing the electrical connections of the controller and without danger of contact with the terminals or conductors within the controller casing. The

above and other advantages will be apparent to those skilled in the art to which my invention appertains.

I claim as my invention:

1. In a controller, the combination with 70 a switch mechanism comprising a pair of members, one of which is provided with integral projecting portions and the other of which is provided with coacting recesses to form a pivotal connection between said 75 members, of a contact member secured to one of said members.

2. In a controller, the combination with a 80 casing having a stationary portion and a removable portion, and an actuating member, of a bearing member for said actuating member, and a member rigidly secured to said bearing member for securing said bearing member to said stationary portion and having means for securing said removable 85 portion to said stationary portion.

3. In a controller, the combination with a 90 casing, and an actuating member, of a bearing member for said actuating member, and a member molded therein for securing said bearing member to said casing.

4. In a controller, the combination with a switching device, and a casing therefor, of 95 means for controlling said switching device, and a bearing member for said controlling means having means rigidly secured to said bearing member for attaching said bearing member to said casing.

5. In a controller, the combination with a 100 transformer, a fuse block and a containing casing for said devices, of common means for retaining the parts of said transformer in operative relation and for securing said transformer and said fuse block to said casing.

6. In a controller, the combination with a 105 member having a plurality of projections at right angles thereto, of a member pivotally mounted upon a pair of said projections, a spring between said pivotally mounted member and a third of said projections, and a contact member carried by one of said members.

7. In a controller, a sheet-metal member 115 having a plurality of arms provided with annular projections, several of said projections forming bearings for said member, a roller carried by others of said projections, and a contact finger supported by said member.

8. In a controller, the combination with a 120 stationary contact member and a stationary sheet-metal support, of a sheet-metal member carried by said support, said member having integral bearing portions for coacting with said support, and a movable contact member secured thereto.

9. In a controller, the combination with a 125 member having a body portion and a plurality of projecting arms and means for co-

acting with a pair of said arms to pivotally support said member, of a spring between said supporting means and said member and a contact element carried by said body portion.

10. In a controller, the combination with a member having a plurality of projecting portions, of a member pivotally supported thereby having integral annular projecting portions to provide bearing surfaces, a rotatable member for coacting with said annular projections, and means for actuating said rotatable member.

11. In a controller, the combination with a pair of members having arms, of integral projecting portions on a part of said arms for providing a pivotal connection to the other arms.

12. In a controller, the combination with a pair of members having arms, of integral annular projecting portions on a part of

said arms for providing a pivotal connection to the other arms.

13. In a controller, a stationary member provided with a pair of oppositely extending arms and a spring supporting arm, a contact member pivotally mounted between said first arms, a spring on said supporting arm and engaging said contact member, and means for opposing the action of said spring.

14. In a controller, the combination with a support, of a member secured thereto having a pair of arms, a contact member pivotally supported between said arms, a flexible shunt connected to said contact member, and common means securing said shunt and said first-named member to said support.

In testimony whereof, I have hereunto subscribed my name this 31st day of May, 1916.

CHARLES H. HODGKINS.
